DESIGN FOR A GLOBE

Robert F. Schleicher, New York, N. Y., assignor to
Edward L. Silverman, New York, N. Y.

Application July 13, 1935, Serial No. 57,619

Term of patent 3½ years

To all whom it may concern:

Be it known that I, Robert F. Schleicher, a citizen of the United States and residing at New York, in the county of Nassau and State of New York, have invented a new, original, and ornamental Design for Globe, of which the following is a specification, reference being had to the accompanying drawing, forming part hereof, and in which

Fig. 1 is a side elevational view of a globe showing my new design, and

Fig. 2 is a top plan view thereof.

I claim:

The ornamental design for a globe, substantially as shown.

ROBERT F. SCHLEICHER.
